UNITED STATES PATENT OFFICE.

JOEL C. R. PALMER, OF BROOKLYN, NEW YORK, ASSIGNOR TO WESTERN ELECTRIC COMPANY, OF NEW YORK, N. Y., A CORPORATION OF ILLINOIS.

TELEPHONE-TRANSMITTER.

1,132,613.

Specification of Letters Patent. Patented Mar. 23, 1915.

Application filed April 15, 1912. Serial No. 690,844.

To all whom it may concern:

Be it known that I, JOEL C. R. PALMER, citizen of the United States, residing at Brooklyn, in the county of Kings and State of New York, have invented a certain new and useful Improvement in Telephone-Transmitters, of which the following is a full, clear, concise, and exact description.

This invention relates to telephone transmitters, and has for its object to provide a transmitter structure in which the detrimental effect, due to an inactive mass of granular carbon or other comminuted material, is eliminated, and the transmitting qualities otherwise improved.

In the commonly known type of solid-back transmitter employing comminuted material as a resistance-varying medium, there has been a portion of the comminuted resistance-varying material which is practically inactive due to the fact that it has settled in the base of the button chamber and is very slightly agitated by the movement of the electrodes. This mass is, therefore, of relatively low resistance and forms a shunt to the path which is actually subject to variation. In accordance with this invention the detrimental feature of this shunt is obviated by so shaping the electrode chamber and adjusting the sizes of the electrodes that the percentage of the inactive material in the button is very small compared to the total amount, and is restricted to an area such that no portion of it is in contact with

one of the electrodes, and any current which has a path through such inactive material must pass also through the material undergoing the maximum agitation. The structure preferably employed for accomplishing this result comprises a chamber, the wall of which is sloped or tapered to form the frustum of a cone and has located in the smaller end thereof an electrode of the same diameter as said smaller end. Located in the

opposite side of said chamber is a second electrode having a larger area than the area of the first electrode exposed to the comminuted material in the chamber, the exposed area of the second electrode being so related to the chamber that the small amount of inactive material is restricted to a small area at the margin of said larger electrode, which area is a greater distance from the smaller electrode than is any point on the exposed surface of the electrode of larger

area. The larger electrode may be formed of rigid material and secured to a flexible diaphragm of insulating material, or said electrode may be formed of flexible metal, such as gold, of sufficient area to cover the front of the chamber and have its inner surface near the margin thereof covered with insulating material to expose only a portion thereof to the comminuted material, the exposed area in both forms being practically the same. Any advantage in either of the structures, however, is probably in favor of the electrode of rigid material inasmuch as in the case of the electrode of rigid material the agitation is substantially uniform throughout the surface of said electrode, whereas in the use of the flexible electrode the maximum disturbance occurs in the central portion of the chamber and the amount of action decreases rapidly from the center outwardly toward the margin of the electrode.

Another feature of this invention relates to a structural detail whereby the minimum number of parts are used for constructing the button, and this feature consists in hollowing out the metal button supporting the electrodes to the shape of the chamber desired and applying a coating of suitable insulating material thereto, thus avoiding the use of a specially formed insulating member for the wall of the chamber, the result being to both cheapen and improve the structure.

In the drawings in which this invention is illustrated with electrodes of rigid material—Figure 1 is a sectional elevation of a transmitter embodying the invention; and Fig. 2 is a view of the transmitter parts of the invention separated and in position for assembly.

In Fig. 1 of the drawings, 5 designates the usual mouthpiece secured in a screw-threaded opening in a face plate 6. Secured to the rear of this face plate 6 is a metal bridge piece 7 provided with a centrally located aperture 8 through which is inserted a metallic block or support 9 for the transmitter button parts. The block 9 is provided on the outer end with a shoulder which bears against a terminal member 10 surrounding said block 9 and separated from the outer face of the bridge 7 by means of an insulating strip 11. The inner end of the block 9 is screw-threaded to receive

- a clamping ring 12 adapted to press against a washer 13 of insulating material surrounding said block 9 and fitted into a recess 14 of the inner face of the bridge piece.
5. The chamber for the electrodes and comminuted material is as follows: A metal cup 18 having a stem 19 thereon which extends through an opening in the block 9 is provided with a sloping or tapering inner wall 20 which is the shape of the frustum of a cone. The cup is provided with exterior screw-threads adapted to receive a metal clamping ring 21 between which and the edge of the cup is clamped a mica diaphragm 22 to which is secured a carbon electrode button 23. Located upon the opposite side of the cup is a second carbon electrode 24 secured to a metal disk 25 having a screw-threaded stem 26 engaging a screw-threaded aperture in the stem 19 of the cup 18. As shown, the electrode 24 is the same diameter as the smaller diameter of the cup wall 20, and is fitted into said cup wall so that the exposed face of the said electrode 25 is flush with the end of the cup wall. The electrode 23 is larger in diameter than the electrode 24 but not so large as the largest diameter of the conical chamber. The wall of the chamber is coated as shown at 15 30 with an insulating compound of any suitable form which is applied in a liquid state and subsequently hardened upon the wall. Secured to the mica disk 23 is a stud 30 the outer end of which is provided with an insulating knob 31 in engagement with an indentation 32 in a metal diaphragm 33 resting against a strip 34 of insulation which bears against the inner face of the face plate 6. Bearing against a collar 35 on the stud 40 30 is a damping spring 38 the outer end of which is attached to the inner face of the bridge piece 7. The damping spring 38 is insulated from the bridge piece 7 but is in electrical connection with a terminal block 45 located upon the opposite face of said bridge piece 7 but insulated therefrom. The block 40 constitutes the terminal of the transmitter with which the movable electrode 23 is connected. The terminal for the stationary electrode 24, if the transmitter is to be used as an insulated transmitter, is connected with a binding screw 43 secured in the member 10 or if the instrument is to be grounded, a ground wire 44 will be led 50 from the binding screw 43 along the bridge piece 7 and attached at its opposite end to a clamping screw 45. In this case, a bell 48 inclosing the transmitter parts and adapted for connection with a desk stand or other suitable subscriber set, will be grounded.
- By referring to the drawing it will be noted that the relative sizes of the two electrodes 23 and 24 and the slope of the wall 60 20 is such that the distance from any point of the smaller electrode 24 to the comminuted material beyond the margin of the larger electrode 23 is greater than the distance from any point of said smaller electrode 24 to the larger or movable electrode 23. Thus it is evident that any current having a path through the comparatively inactive material beyond the margin of the larger electrode must also pass through the active material between the two electrodes, thus undergoing the maximum change and avoiding the shunting of the active path.
- The feature of applying the insulating material directly to the wall of the metal chamber has advantages over prior forms of buttons in that it avoids the use of extra piece parts such as insulating strips which were necessary formerly when the chamber was formed in metal and the extra parts necessary for retaining the insulating strips and completing the terminal connections to the electrodes.
- I claim:
1. A telephone transmitter having an electrode chamber with a tapered wall, an electrode at one end of said chamber, a second electrode larger than the first at the opposite end of said chamber and having a diameter less than the largest diameter of said chamber. 95
  2. A telephone transmitter having an electrode chamber with a tapered wall, a stationary electrode located at the smaller end of said chamber, a closure for the larger end of said chamber, and an electrode carried by said closure having an area larger than the area of said stationary electrode and smaller than the total area of said closure. 100
  3. A telephone transmitter having an electrode chamber with a tapered wall, comminuted material in said chamber, a stationary electrode located at the smaller end of said chamber, a closure for the larger end of said chamber, said closure presenting a central conducting surface and a peripheral non-conducting surface to said comminuted material, said conducting surface having an area greater than the area of said stationary electrode. 110
  4. A telephone transmitter having an electrode chamber the shape of the frustum of a cone, an electrode of the same diameter as the smaller end of said chamber secured therein, and a movable electrode of rigid material located upon the opposite side of said chamber, said movable electrode being of greater diameter than the first-mentioned electrode and of less diameter than the largest diameter of said chamber. 120
  5. A telephone transmitter having an electrode chamber with a tapered wall, comminuted material in said chamber, an electrode at the smaller end of said chamber, a second electrode located in the oppo- 130

site end of said chamber, said second electrode having exposed to the comminuted material in the chamber an area greater than the area of said first-mentioned electrode but less than the area of the larger end of said chamber.

6. A telephone transmitter having an electrode chamber with a tapered side wall, comminuted material in said chamber, an electrode located at the smaller end of said chamber, a movable electrode of larger diameter at the opposite end of said chamber, said larger diameter electrode having a conductive area exposed to said comminuted material of less diameter than the largest diameter of said electrode chamber.

7. A telephone transmitter having an electrode chamber with a tapered wall, comminuted material in said chamber, a sta-

tionary electrode located in one end of said chamber, a movable electrode located at the opposite end of said chamber and having exposed to said comminuted material an area greater than said stationary electrode but less than the area of the larger end of the chamber, the distance from said stationary electrode to said movable electrode being less than the distance from said stationary electrode to the comminuted material beyond the margin of the exposed area of said movable electrode.

In witness whereof, I hereunto subscribe my name this 12th day of April A. D., 1912.

JOEL C. R. PALMER.
